UNITED STATES PATENT OFFICE.

CHARLES F. PIKE, OF PHILADELPHIA, PENNSYLVANIA, ASSIGNOR, BY MESNE ASSIGNMENTS, TO THE NATIONAL ANTI SEWER GAS COMPANY, OF NEW JERSEY.

WATER-CLOSET.

SPECIFICATION forming part of Letters Patent No. 298,310, dated May 6, 1884.

Application filed August 3, 1881. Renewed April 12, 1882. (No model.)

To all whom it may concern:

Be it known that I, CHARLES F. PIKE, a citizen of the United States, and a resident of the city and county of Philadelphia, in the State 5 of Pennsylvania, have invented certain new and useful Improvements in Water-Closets, of which the following is a specification, reference being had to the accompanying drawings, wherein—

10 Figure 1 is a longitudinal vertical section of my improved water-closet, showing the pan in its normal position. Fig. 2 is a like view showing the pan dumped. Fig. 3 is a plan of the receiver and operating-levers for the pan 15 and receptacle seals therefor. Fig. 4 is a vertical transverse section of water-closet with pan in its normal position. Figs. 5 and 6 are sections illustrating modifications of my invention, and Figs. 7 and 8 are detail perspectives.

My invention has relation to water-closets having a pan and receiver, and has for its object to provide a running seal for the pan, its operating mechanism, and receiver, whereby 25 the closet is hermetically sealed at all points against the escape of sewer-gas or odors therefrom.

My invention accordingly consists of the novel combination, construction, and arrangement of parts, as hereinafter specifically described and claimed.

Referring to the accompanying drawings, A represents the bowl of a water-closet, B the receiver thereof, and C the pan. The latter is riveted or suitably secured at *c* to a lug, *d*, formed on shaft D. Said shaft has its bearings in lugs *B*² *B*², depending from the receiver-lid B', as shown. The joint between said lid and receiver is suitably packed to prevent 35 gases escaping therefrom. Such construction avoids the perforation of the walls of the receiver for said bearings; consequently no sewer-gas or excrementitious odors pass out of the receiver through the pan-shaft journal-bearings. The pan C is formed or provided with a chamber or receptacle, E. Said parts have communication with each other by means 40 of a tube, *e*, located, as shown, near the upper edges of said vessels, whereby water passing into either of said parts will rise to the

same level in both, said tube also acting to hold said pan and receptacle rigidly together.

b is an opening in the top or lid of the receiver, and from which depends a flange or tube, *b'*, as shown. Said tube is of sufficient 55 length to enter the receptacle E, and the latter is made longer or deeper than the pan C, so that when said pan is in a horizontal position the plane of the upper edge of the receptacle will be above that of the upper edge of 60 the pan; hence any water supplied to said receptacle will pass into the pan and overflow therefrom, and not from the receptacle. Said receptacle is made of sheet-iron galvanized to prevent corrosion; or it may be made of 65 any other suitable material and appropriately finished. It is secured at *e* to a lug, *d'*, which is also cast or formed on shaft D, the latter also passing through said receptacle, as shown. Said lug is extended to form a crank, *d*², for 70 rotating said shaft. To said crank is attached a link, *d*³, which has its position within the receptacle E.

F is a rod passing through the tube *b'*, and is connected at one end to the link *d*³, and at 75 its opposite end to lever G, pivoted at *g* to lug *g'*, formed on the receiver-lid B', so that when said lever G is moved, as hereinafter set forth, the pan and receptacle will, through the medium of the rod *F*, link *d*³, and crank *d*², be 80 dumped and returned to its normal position, as hereinafter explained.

H is the water-supply pipe provided with a cock, *h*, secured to the receiver-lid in any suitable manner; and *H'* is the flushing-pipe 85 for the bowl. *H*² is a pipe branching off from the supply-pipe, or from the cock *h*, or just in advance of the flushing-pipe *H'*, so that when the supply is cut off from the latter said water will pass to branch pipe. The latter 90 passes through an opening, *b*², in the lid B' of the receiver, and through a tube, *b*³, formed integrally on said lid around said opening. Said tube depends down into the receptacle E, its end dipping below the line of the inter- 95 communication of said receptacle and pan. Said branch is a pipe having a small bore, so that only a minimum head of water can pass therethrough, the result whereof is that the water flowing through said branch finds its 100

way into the receptacle, and thence through pipe e to pan, to provide for a continuously-running seal for said parts.

I represents a lever pivoted at i to a lug, 5 i' , cast on the receiver-lid, and is provided at its end i^2 with an eccentric slot, i^3 , which receives a pin projecting from the cock-piston h^3 . The opposite end of said lever is formed with a concentric slot, i^4 , into which enters a 10 pin, g^2 , projecting from lever G.

The operation is as follows: Said parts being arranged as shown in Fig. 1 the water from the supply - pipe continuously passes into branch H^2 , and from thence into receptacle 15 E, rising therein until it reaches the tube e , whereupon it passes through the latter into pan C. The lower edges of tubes $b' b^3$ and of the water-closet bowl are then below the level of said water, and are sealed thereby.

20 When the closet has been used and it is desired to drop the pan, the handle L is lifted to raise lever I. The slot i^3 therein permits the lever to be raised the length of said slot before lever G begins to move. Consequently, 25 such advanced movement of lever I causes its slot i^3 to open cock h , and allows the water to pass through pipe H' to flush and wash the sides of the bowl before the pan begins to move or drop. Consequently, any splashings 30 of fecal matter therein are removed from the sides of the bowl and washed into the sealing-water above the pan, so that when the lever G begins to move by the continued movement of handle L to depress rod F, and link d^3 to turn 35 crank d^2 to oscillate the shaft D to dump receptacle and pan, all the fecal matter in the bowl is then in the sealing-water, and thereupon immediately falls into the receiver. The flushing-water still continues to run, and will 40 do so even after the handle L is pressed downwardly, owing to said slot i^3 in the lever. When the pan is dumped, it is emptied of its sealing-water. The receptacle is also nearly so emptied; but when the levers are reversely 45 moved to cause said parts to return to their normal positions and close cock h , the last portion of water passing through the flushing-pipe is sufficient to fill said pan and receptacle to seal bowl A and tubes $b' b^3$, as above described.

50 If not, the water now passing through branch soon refills such parts to form the seal therefor, as above set forth. If desired, for the better regulation of the amount of water passing through said branch, it may be furnished 55 with a pet-cock, M, as shown in Fig. 8, whereby the quantity of such water may be increased or diminished at pleasure or according as circumstances may dictate.

If desired, instead of attaching the receptacle to the shaft D, it may be cast integrally on 60 one of the sides of the receiver B, as shown at E in Fig. 6, in which case intercommunication with pan will have to be provided for either by making that portion of said shaft between the receptacle and the pan hollow, as 65 shown at m , or said parts may be connected by a flexible pipe or hose, as indicated at m' ; or the pan and the receptacle may be formed in one, as shown in Fig. 5; but I deem the construction shown in Fig. 1 the preferable mode, 70 on account of the ease and cheapness of construction, and for the further reason that all dissolved or finely-divided particles of fecal matter are held solely in the pan, and thereby prevented from entering said receptacle to adhere to and clog the mechanism therein. Consequently, said mechanism will at all times be 75 entirely free of such matter, and will not therefore be liable to get out of order.

So much of the foregoing specification as relates, broadly, to running-water seals for water-closets I hereby withdraw from this application, so as to make the same a subject for a separate and subsequent application for a patent. 80

85 What I claim as my invention is—

1. In a water-closet, the combination of the following elements, viz: a receiver, a bowl, a pan therefor having an attached and an inter-communicating receptacle, which receives a 90 flange depending from an opening in the receiver, and an operating-lever for said pan connected to said receptacle, substantially as shown and described.

2. The combination, in a water-closet, of a 95 sealing - pan, mechanism for operating the same, a water-supply pipe having a cock, with flushing-pipe for the bowl of the closet, and a branch pipe or conduit from said water-supply pipe leading to the pan, for effecting a 100 running-water seal therefor, substantially as specified.

3. The combination of bowl A, receiver B, formed with lugs $B^2 B^3$, depending tubes $b' b^3$, with pan C, shaft D, and water-supply pipe H, 105 having branch H^2 , substantially as and for the purpose set forth.

In testimony whereof I have hereunto set my hand this 28th day of July, 1881.

CHAS. F. PIKE.
